Inventor

Charles W. Lavers

Wm. H. Babcock & Son
Attorneys.

UNITED STATES PATENT OFFICE.

CHARLES WILLIAM LAVERS, OF HALIFAX, NOVA SCOTIA, CANADA.

DETACHABLE SHOE HEEL OF THE EMBEDDED-WASHER TYPE.

Application filed June 29, 1920. Serial No. 392,872.

To all whom it may concern:

Be it known that I, CHARLES WILLIAM LAVERS, a subject of the King of England, residing at Halifax, in the county of Halifax, Province of Nova Scotia, and Dominion of Canada, have invented certain new and useful Improvements in Detachable Shoe Heels of the Embedded-Washer Type, of which the following is a specification.

10 This invention relates to shoe heels of the two member detachable type, particularly to that type wherein attaching washers are embedded in the material of the removable member, which is generally of rubber, and 15 cooperate with interlocking means carried by the permanent member.

The objects of the invention are to provide such a type of washer and cooperating interlocking means which will permit of 20 ready and expeditious engagement and disengagement of the members, to provide means for locking said members in normal or assembled position, to provide easy means for unlocking said members, to provide a 25 firmer grip of the washer by the material surrounding the same, to obtain the added resiliency or flexibility of the present type of washer heel while retaining the advantage of firmer grip and slidable engagement here- 30 tofore known in the plate type of removable heel, and to simplify and otherwise improve the article and to reduce the cost of manufacture and increase the life of the article, all of which objects, among others, are ac- 35 complished by the construction, combination and arrangement of parts to be herein- after more particularly set forth, described and claimed.

In the accompanying drawings:

40 Figure 1 represents a vertical cross-section through a form wherein an integral piece is dished and bent over to protect the opening, forming a box to exclude the material of the detachable member during the 45 molding operation.

Figure 2 represents a vertical cross-section through a further modification, wherein in an integral part of the base of the washer is bent over to make a closed box, and

50 Fig. 3 is a cross-section of the heel with the washer of Fig. 2, applied.

The preferred form of the invention is of box-like or pocket construction, as in Figs. 1 and 2, having a key-hole or other suitable

opening in one side to receive a headed or 55 similar cooperating element and provided with laterally extending flanges or flange elements, the whole being adapted to be embedded in the plastic material of a shoe heel. The two forms shown are of slightly differ- 60 ent shape, one having pronounced side walls while the other has the side walls merged more into the bottom.

In Figure 2 the integral metal flap 6 is illustrated as turned back flat to close the 65 bottom of the struck-up or box portion and prevents the entrance of the liquid material during the molding operation. This construction, as stated, prevents the entry of 70 rubber during the molding operation and thereby facilitates the entry of the heads 7 of the nails 8 into their corresponding co- 75 operating slots 5.

The detachable member 9 is provided with a plurality of any type of these washers 1 75 embedded in it to an equal depth and which are provided with orifices or headed slots 5 of any suitable form permitting sliding interlocking engagement with the nails or en- 80 gaging projecting members 8 which are driven through the base plate 11 into the permanent heel member 10 and kept in proper alignment by said baseplate 11 for engagement with the separate embedded washers 1 in the detachable member 9. 85

It will be noted that the material of the washers 1 adjacent the corners of the headed slots 5 is struck-up or inwardly inclined to form lips 12, to facilitate the easy engagement between the heads 13 90 of the nails 8 and the under face of the washers 1 adjacent the narrow parts or stems of the headed slots 5. The nails 8 are each formed with a shoulder 14 adapted to keep a predetermined spacing between its head 7 95 and the plate 11 which is provided with perforations 15 only large enough to admit the shanks of said nails. The specific plate construction and the specific nail construction, also the struck-up or upwardly inclined lips 100 12, however, are not particularly claimed herein, but are mentioned as being the most suitable method of construction and opera- 105 tion.

Since many apparently widely different 105 embodiments of my invention might be made, such embodiments being within the spirit and scope of the following claims, it is

intended that this specification shall be regarded as illustrative rather than limiting in detail.

Having thus described my invention, what I claim as new and desire to secure by Letters Patent is:

1. In combination with a detachable shoe heel of plastic material, an attaching element of box-like construction closed on all sides and provided in one side with an opening to receive a cooperating attaching means, said element being embedded in the plastic material of said heel and by its box-like construction excluding from its interior the plastic material of said heel.

2. In combination with a detachable shoe heel of plastic material, an attaching element of box-like construction closed on all sides and provided in one side with a slot to receive a co-operating attaching means, and a peripheral flange extending therefrom, said attaching element being embedded in the plastic material of said heel and by its box-like construction excluding from its interior the plastic material of said heel.

3. In combination with a detachable shoe heel of plastic material, an attaching washer comprising a plate of metal having one part dished or depressed out of its normal plane, one side of said washer being provided with an opening, said washer being embedded in plastic material of said

heel and by its box-like construction excluding from its interior the plastic material of said heel.

35

4. In combination with a detachable shoe heel of plastic material, an attaching washer completely closed on all sides and comprising a plate of metal having one part dished or depressed out of its normal plane, said element being embedded in the plastic material of said heel and by its box-like construction excluding from its interior the plastic material of said heel.

40

5. In combination with a detachable shoe heel of plastic material, an attaching washer completely closed on all sides and comprising a plate of metal having one part dished or depressed out of its normal plane and having an opening in one side, and a peripheral flange extending from said washer and adapted to be embedded, said washer being embedded in the plastic material of said heel and by its box-like construction excluding from its interior the plastic material of said heel.

45

In testimony whereof, I have signed my name to this specification in the presence of two subscribing witnesses.

50

CHARLES WILLIAM LAVERS.
